C. F. ALLEN,
DOOR CONSTRUCTION FOR FREIGHT CARS,
APPLICATION FILED MAR. 3, 1914.

1,141,513.

Patented June 1, 1915.

UNITED STATES PATENT OFFICE.

CHARLES F. ALLEN, OF LOS ANGELES, CALIFORNIA.

DOOR CONSTRUCTION FOR FREIGHT-CARS.

1,141,513.

Specification of Letters Patent.

Patented June 1, 1915.

Application filed March 3, 1914. Serial No. 822,126.

To all whom it may concern:

Be it known that I, CHARLES F. ALLEN, a citizen of the United States, residing at Los Angeles, in the county of Los Angeles, State 5 of California, have invented new and useful Improvements in Door Construction for Freight-Cars, of which the following is a specification.

This invention relates to flush closing 10 doors for box cars, and particularly pertains to improvements in that form of box car doors illustrated in Patent Number 993,744 issued to me May 30th, 1911.

It is the object of this invention to provide an overhead rolling support for a car door by which it may have a free lateral movement to and from the body of the car when moving it in and out of a door opening, and at the same time permit of its 20 movement longitudinally of the car to effect the opening or closing of the door opening.

Another object is to provide means for concealing the joints between the door and its casing, whereby the insertion of tools for 25 prying the door open can be effectively prevented.

A further object is to provide a simple means for shifting the rear edge of the door outwardly to clear the door casing when 30 opening the door.

The manner of obtaining the above objects is illustrated in the accompanying drawings, in which:

Figure 1 is a front elevation of a part of 35 a box car showing a portion thereof where the flush door is located, with the door in its closed position. Fig. 2 is a horizontal section on the line 2—2 showing the door in its open position. Fig. 3 is a corresponding view showing the door in its closed position and illustrating it in an intermediate 40 position in dotted lines. Fig. 4 is a detail vertical section in elevation on the line 4—4 of Fig. 1 as viewed in the direction indicated by the arrows. Fig. 5 is a detail horizontal section on the line 5—5 of Fig. 1 illustrating the initial step in opening the door, whereby the rear edge of the door is moved outwardly clear of the door casing. 45 Fig. 6 is a detail section illustrating an au-

tomatic stop for engaging the door in its open position, and for preventing its closing when the car is being moved from place to place.

More specifically, 7 designates the car 55 body, 8 designates the door opening therein in which the door 9 is adapted to be introduced with its outer face flush with the outer face of the car body 7.

Mounted on the car body 7 above the 60 opening 8 and extending on one side thereof, is a horizontally disposed channel iron track 10 which is secured to the car body in any suitable manner and is covered by a protecting shield 11 having a depending apron 12 65 which extends to a point adjacent the lower edge of the track 10 and is spaced therefrom to form a longitudinal slot in which the door hangers 13 travel.

The door hangers 13 are fitted with spindles 14 at their upper ends on which rollers 15 adapted to travel in track 10 are revolvably mounted. The lower ends of the door hangers 13 are fitted with oppositely extending spindles 16 on which rollers 17 are revolvably mounted. These rollers are positioned in oppositely horizontally extending channels 18 formed in brackets 19 secured to the car door 9 adjacent its upper edge. The channels 18 extend at right angles to 80 the door and in engaging the roller 16 form a rolling support therefor which will permit a free limited movement of the door at right angles to the face of the car so that it can be readily moved in and out of its 85 closed position.

Any number of the hangers may be provided as may be desired according to the length of the car door. In this case, a pair is shown with one arranged adjacent the 90 forward edge of the door and the other disposed adjacent its rearward edge.

As a means for protecting the joint at the forward vertical edge of the door, a shield plate 20 is provided. This plate is 95 rigidly secured to the outer face of the car body 7 and has an outwardly flared lip portion 21 on its outer vertical edge which extends beyond the edge of the door opening as shown in Fig. 2. The lip 21 by being 100

flared outwardly serves to direct the forward edge of the door therebehind when the latter moves into its closed position.

Extending parallel with the vertical rear edge of the door opening 8 is a cleat 22 which is hinged to the side 7 on the car adjacent its upper and lower ends by means of pivot pins 23, which pins pass through lugs 24 on a face plate 25 and through spaced lugs 26 on the cleat 22. The cleat 22 is designed to be swung on the pivot pins 23 to extend over the joint between the rear edge of the door and its casing when the door is in its innermost and closed position, and is intended to be locked in this position to conceal the joint, and at the same time prevent opening of the door. For this purpose a handle 27 is formed on the cleat 22 near its lower end, which handle is formed with a slot 28 to receive a staple 29 on the door through which a bolt 30 is passed and secured by the usual seal 31.

Mounted on each pivot pin 23 and between each pair of lugs 26 is a short lever 32 which extends in a shallow recess 34 formed in the door casing, and has a projecting finger 35 on its inner end, which is arranged to engage the inner face of the door 9 when the latter is in its closed position as particularly shown in Fig. 5. The outer end of the levers 32 extends outwardly a short distance from the pivot pin 23 into the path of travel of the cleat 22 when the latter is swung to its open position in such manner that when this movement of the cleat is effected, the levers 32 will be rocked on the pivot pins 23 thereby shifting the door 9 laterally on rollers 17 on the rear hanger 13 to move the rear edge of the door clear of the door casing as illustrated in dotted lines in Fig. 5. The door 9 may then be readily shifted longitudinally on the track 10; the rollers 17 permitting its ready transverse movement to a distance sufficiently far from the side of the car that the inner face of the door will clear the cleat 22 in moving the door to its rear-most position.

The lower end of the door is guided in the usual guide brackets 36, the foremost edge of which is fitted with a weighted pawl 27 as shown in Fig. 6 by which the forward edge of the door is engaged to prevent shifting of the door longitudinally when in its open position on movement of the car; the rear edge of the door being engaged by a stop 38 on the side of the car.

The operation of the invention is apparent from the foregoing; it being readily seen that in moving the door longitudinally from the open position shown in Fig. 2 to the closed position shown in Fig. 3, the door may be freely advanced on the rollers 17 and track 10 and then directed inwardly as indicated in dotted lines in Fig. 3 so as to position the forward edge of the door be-

hind the lip 21 of the shield plate 20; the transverse movement of the door being facilitated by reason of the rollers 17 on which it is supported. When the rear edge of the door is positioned opposite the rear edge of the opening, the door is shifted laterally on the rear rollers 17 so as to extend within the door casing with its outer face flush with the outer face of the car body 7. In moving into this position the rear edge of the door 9 engages fingers 35 on the levers 32 and moves the levers 32 to their normal position which is limited by the vertical wall of the recess 34, whereupon the cleat 22 is swung to its closed position to cover the joint between the rear edge of the door and its casing, and is locked by means of the bolt 30 as hereinbefore described. By providing the foregoing construction, the door is effectively locked at its vertical edges to prevent its being pressed upwardly by malicious persons in attempting to effect an entrance to the car, and the track 10 and rollers 17 are shielded by the plate 11 and apron 14 to prevent their being tampered with. The shield 20 and cleat 22 with the apron 12 also serve to protect the joints of the door against the passage of water therethrough and thus render the door water-tight.

What I claim is:

1. The combination with a car having a door opening, of a suspended door adapted to enter said opening and be positioned flush with the wall of the car, and means for forcing said door into and out of said flush position, said means including a pivoted lever arranged to engage the rear side of the door near one edge thereof, and a cleat separate from said lever and pivoted at the same fulcrum point, said cleat being arranged to engage said lever and operate it to force the door out from flush position, said cleat when moved in the reverse direction forcing said door to its flush position.

2. The combination with a car having a door opening and a door adapted to fit within said opening, of means for forcing said door laterally into and out of the door opening, said means including a pair of pivoted levers, one of which is provided with a finger at its inner end to engage the rear side of the door and an arm at its outer end adapted to be engaged by the other lever, said levers being independently movable.

3. The combination with a car having a door opening, of a suspended door adapted to enter said opening and be positioned flush with the wall of the car in which said opening occurs, and means for forcing the door into and out of said flush position, said means including a cleat pivoted to the side wall of the car adjacent one vertical edge of the door opening therein and when in closed position fitting over the joint between the door edge and the edge of the opening,

and a pair of separate, short levers pivoted on the same pivots as said pivoted cleat, each of said levers having a finger on its inner end adapted to engage the rear side 5 of the door and an arm on its outer end which is engaged by the cleat when the cleat is swung from closed to open position.

In witness that I claim the foregoing I have hereunto subscribed my name this 19th day of February 1914.

C. F. ALLEN.
